UNITED STATES PATENT OFFICE

138,067

DESIGN FOR A COMBINATION BABY'S HIGH AND SLEEPING CHAIR

Emanuel R. Morando, New York, N. Y.

Application March 30, 1944, Serial No. 113,085

Term of patent 7 years

(Cl. D15—8)

To all whom it may concern:

Be it known that I, Emanuel R. Morando, a citizen of the United States, residing at New York, in the county of Bronx and State of New York, have invented a new, original, and ornamental Design in a Combination Baby's High and Sleeping Chair, of which the following is a specification, reference being made to the accompanying drawing, forming a part thereof, in which:

Figure 1 is a front elevational view of a combination baby's high and sleeping chair, showing my new design.

Figure 2 is a rear elevational view of the same design shown in Figure 1.

Figure 3 is a side elevational view thereof.

Figure 4 is a similar side view with the high chair extended in a sleeping position, and with the front table-leaf portion open as shown.

Figure 5 is a top plan view of the high chair on a reduced scale, showing the table leaves swung outwardly in their open position.

I claim:

The ornamental design for a combination baby's high and sleeping chair, as shown and described.

EMANUEL R. MORANDO.
